CLAIM

The ornamental design for a skinny can cooler, as shown and described.

DESCRIPTION

FIG. 1 is a top perspective view of a skinny can cooler, showing my new design;

FIG. 2 is an exploded view thereof;

FIG. 3 is a perspective view with the lid coupling attached thereof;

FIG. 4 is an exploded view with the lid coupling attached thereof;

FIG. 5 is a perspective view without the lid coupling thereof;

FIG. 6 is an overhead view without the lid coupling thereof;

FIG. 7 is a top plan view without the lid coupling thereof;

FIG. 8 is a bottom plan view without the lid coupling thereof;

FIG. 9 is a front view with the lid coupling attached thereof;

FIG. 10 is a front right-side view without the lid coupling attached thereof;

FIG. 11 is a front left-side view without the lid coupling attached thereof;

FIG. 12 is a rear right-side view without the lid coupling attached thereof; and,

FIG. 13 is a rear left-side view without the lid coupling attached thereof.

The stippling marks shown in FIGS. 2-4 represent a contrast in appearance.
